UNITED STATES PATENT OFFICE.

ALEXANDER NYMAN, OF WILKINSBURG, PENNSYLVANIA, ASSIGNOR TO WESTINGHOUSE ELECTRIC & MANUFACTURING COMPANY, A CORPORATION OF PENNSYLVANIA.

STARTING MECHANISM FOR AUTOMOBILES.

Application filed November 20, 1920. Serial No. 425,407.

To all whom it may concern:

Be it known that I, ALEXANDER NYMAN, a citizen of the United States, and a resident of Wilkinsburg, in the county of Allegheny and State of Pennsylvania, have invented a new and useful Improvement in Starting Mechanisms for Automobiles, of which the following is a specification.

My invention relates to starting mechanisms for automobiles and, particularly, to starting mechanisms wherein pinions are moved axially into mesh with engine gear wheels.

One object of my invention is to provide a starting mechanism that shall comprise a flat coil spring for connecting a pinion to the motor armature and for effecting axial movement of the pinion and that shall also comprise centrifugally-operated levers which normally lock the pinion against rotation when the motor is standing still.

In automobile-starting mechanisms of the type having a motor pinion that is movable axially into mesh with an engine gear wheel, considerable trouble has been experienced heretofore in effecting axial movement of the pinion without damaging the gear teeth. In a starting mechanism having a spiral thread formed on the armature shaft for effecting axial or longitudinal movement of the pinion, the gear teeth are often damaged by reason of pinion teeth meeting the engine-gear-wheel teeth end to end. Moreover, it is necessary, in such systems, to operate the motor within certain speed limits to obtain meshing when the pinion teeth register properly with the gear-wheel teeth.

In a starting mechanism constructed in accordance with my invention, a pinion is rotatably and slidably mounted upon the shaft of the starting motor. A flat coil spring, which is mounted on the armature shaft between the pinion and the frame of the motor, serves to effect axial movement of the pinion upon starting of the motor. One end of the spring member is directly connected to the armature shaft and the other end thereof is directly connected to the motor pinion.

The frame of the starting motor is provided with an end bracket having slots cut therein adjacent to the pinion. A plurality of levers, which are pivotally mounted on the motor pinion, are biased to register

with the slots in said end bracket when the starting motor is de-energized. Upon energization of the motor, the pinion is prevented from rotating by the levers which engage the slots in the end bracket. However, the relative movement between the armature shaft and the motor pinion so expands the flat spring as to force the pinion into mesh with the engine gear wheel. Upon meshing of such members, the pivotally mounted levers become disengaged from the slots in said end bracket and are held by centrifugal force away from the motor shaft.

In the accompanying drawing, Figure 1 is a side elevational view of a starting mechanism constructed in accordance with my invention;

Fig. 2 is a side elevational view showing the positions of various parts of the starting mechanism upon meshing of the pinion with the engine gear wheel;

Fig. 3 is a side elevational view of a modification of my invention, and

Fig. 4 is a side view of the spring member which is utilized for effecting axial movement of the motor pinion.

Referring to the accompanying drawing, a motor 1 of any suitable type, is provided for operating an engine gear wheel 2 to start an internal-combustion engine (not shown). The motor 1 comprises a frame 3 having end brackets 4 and 5 and an armature shaft 6 which is provided with any suitable bearings in the end brackets. The end bracket 5 is provided with a plurality of slots 7 for a purpose to be hereinafter set forth.

A motor pinion 8 is slidably and rotatably mounted upon the armature shaft 6 and is adapted to be moved axially into mesh with the engine gear wheel 2 upon energization of the motor. The pinion 8 is provided with a collar 9 which is preferably formed integral therewith. The collar member 9 is provided with a plurality of axially extending supports 10. A flat coil spring 11 is mounted on the armature shaft 6 between the pinion 8 and the armature 12 of the motor. One end of the spring member 11 is fixedly connected to the armature 12 and the other end thereof is fixedly connected to the collar member 9. The diameter of the coil of the spring member is somewhat greater than the diameter of the armature shaft in order that the coils may be separated somewhat upon

relative movement between the armature shaft and the motor pinion.

Each of the supports 10 is provided with a pivotally mounted lever 13 which is biased 5 to register with one of the slots 7 in the end frame by means of any suitable spring member 14.

Assuming the starting mechanism to be in the position shown in Fig. 1 and the motor 10 2 to be energized, relative movement is produced between the armature shaft 6 and the motor pinion 8 by reason of the levers 13 co-operating with the slots 7 in the end bracket 5. Such relative movement between 15 the motor pinion and the armature shaft effects an uncoiling movement of the spring member 11 which reacts on the collar member 9 to move the motor pinion axially into mesh with the engine gear wheel 2. Upon 20 meshing of the pinion with the gear wheel, the levers 13 are withdrawn from the slots 7 in the end frame and, consequently, the pinion is rotated for cranking the engine (not shown). The rotative movement of 25 the pinion 8 and the collar member 9 produces a centrifugal force which holds the levers 13 away from the armature shaft 6, as shown in Fig. 2 of the drawing. It should be noted that, by utilizing a flat 30 spring member for connecting the motor pinion to the motor armature, a larger amount of axial movement of the pinion is effected for a given relative movement between the shaft and the pinion than could be 35 effected by any other type of spring member.

Referring to Fig. 3 of the drawing, a motor 20, having a frame 21 and an armature 22, is provided for operating an engine gear wheel 23 to crank an internal-combustion engine, (not shown). The armature 22 is provided with a shaft 24 which carries a motor pinion 25. The pinion 25 is fixedly mounted upon the armature shaft and is moved axially into mesh with the teeth on 45 the engine gear wheel 23 upon energization of the motor. In this modification, the complete motor is moved axially in place of moving the pinion along the shaft, as in the mechanism shown in Figs. 1 and 2.

50 The motor frame 21 is slidably mounted in a housing 26 of any suitable construction and is attached to such housing by means of a spring member 27, one end of the spring member being fixedly connected to the housing 26 and the other end of the spring member being fixedly connected to any suitable point upon the motor frame 21. The armature shaft 24 carries a centrifugal block 28, and the block serves to support a plurality 55 of pivotally mounted levers 29. The levers 29 are biased by means of spring members 30 to register with slots 31 that are formed in a stationary block 32. The stationary block 32 is preferably mounted on the housing 26.

Upon energization of the motor, relative movement is effected between the motor armature and the motor frame by reason of the locking action of the levers 29. Such relative movement serves to so coil the 70 spring member 27 as to force the complete motor in an axial direction and to effect meshing between the motor pinion and the engine gear wheel. Upon meshing between the pinion and the gear wheel, the levers 29 75 are withdrawn from the slots 31 and, consequently, the pinion 25 is rotated for operating the engine gear wheel to crank the engine. During such operation, the spring member 27 prevents any rotative movement 80 by the frame of the motor. When the engine is started and the motor is de-energized, the spring member 27 moves the complete motor and the pinion 25 towards the left, as shown in the drawing, to de-mesh the pinion 85 and gear wheel.

In the preferred starting mechanism above described, a flat spring member is provided, not only for connecting the motor pinion to the armature, but also for effecting 90 axial movement of the pinion into mesh with the engine gear wheel. Moreover, the spring member serves to withdraw the motor pinion from mesh with the engine gear wheel upon deenergization of the motor. In such starting mechanism, the motor pinion is rotating at a very limited speed upon meshing with the engine gear wheel and, accordingly, is not liable to be damaged in case the pinion teeth meet the engine gear-wheel teeth 100 end to end.

Modifications in the mechanisms and in the arrangement and location of parts may be made within the spirit and scope of my invention and such modifications are, intended to be covered by the appended claims. 105

I claim as my invention:—

1. In a starting mechanism, the combination with a motor and a pinion mounted on the shaft of said motor, of a spring member 110 connected between the motor shaft and said pinion, and centrifugally operable means for locking said pinion against rotation until the pinion occupies a predetermined position relatively to said motor shaft. 115

2. In a starting mechanism, the combination with a motor having a shaft and a pinion mounted on said shaft, of a flat spring wound on said shaft and connected between said pinion and the shaft, said spring serving to move the pinion axially into mesh with the engine gear wheel upon starting of the motor, and centrifugally operated members for preventing rotation of the pinion upon energizing the motor. 120

3. In a starting mechanism, the combination with a motor and a pinion, of means comprising a spring member for connecting said pinion to the motor and for effecting axial movement of the pinion upon starting 125 130

- of the motor, and centrifugally operable means for preventing rotation of the pinion until the pinion occupies a predetermined position along the axis of said shaft.
5. 4. In a starting mechanism, the combination with a motor having a shaft, a pinion, and an engine gear wheel, of means comprising a flat spring member for connecting said pinion to the motor and for effecting axial movement of the pinion into mesh with the engine gear wheel, and centrifugally operated members for locking said pinion to the motor frame when the motor is de-energized.
10. 5. In a starting mechanism, the combination with a motor and a pinion, of means comprising a spring member for connecting the pinion to the motor and for effecting axial movement of the pinion, and means mounted on said pinion for preventing its 20 rotating until the motor has been energized a predetermined length of time.
6. In a starting mechanism, the combination with a motor, and a pinion, of means comprising a flat spring member for connecting said pinion to the motor and for effecting axial movement of the pinion, and levers pivotally mounted on said pinion and normally extending into slots in the frame of the motor.
25. 7. In a starting mechanism, the combination with a motor, the frame of said motor
- having an end bracket with slots cut therein, and a pinion, of means comprising a flat spring for connecting said pinion to the shaft of the motor, levers pivotally mounted 35 on said pinion, and means for biasing said levers into the slots in the motor frame when the motor is de-energized.
8. In a starting mechanism, the combination with a motor, the frame of said motor 40 having an end bracket with slots formed therein, and a motor pinion mounted on the motor shaft, of a flat spring mounted on the motor shaft and connected to the motor shaft and said pinion, said spring serving 45 to effect axial movement of the pinion upon starting of the motor, a plurality of levers pivotally mounted on said pinion, and means for biasing said levers to positions in said slots when the motor is stationary. 50
9. In a starting mechanism, the combination with a motor, and a motor pinion, of a flat spring member for connecting said pinion to the motor and for effecting axial movement of the pinion, a pair of centrifugally operated levers mounted on said pinion, and means for biasing said levers into locked engagement with the frame of the motor. 55
- In testimony whereof, I have hereunto subscribed my name this first day of November, 1920.

ALEXANDER NYMAN.
